UNITED STATES PATENT OFFICE.

WILLIAM BUZBY TYLER, OF CAMDEN, NEW JERSEY.

PROCESS OF TREATING PICTURES.

SPECIFICATION forming part of Letters Patent No. 758,945, dated May 3, 1904.

Application filed February 12, 1904. Serial No. 193,325. (No specimens.)

To all whom it may concern:

Be it known that I, WILLIAM BUZBY TYLER, a citizen of the United States, residing at Camden, in the county of Camden and State of New Jersey, have invented a new and useful Process of Treating Pictures, of which the following is a specification.

My present invention relates to a novel process for treating pictures, my object being 10 to beautify pictures of all kinds by means of a simple and inexpensive process which will serve to illuminate the picture, intensify the coloring thereof, bring out the pictured image in bold relief, and render translucent and 15 give body to the material upon which the image is produced.

The process is practiced in the following manner: A suitable vessel is partially filled with a strong solution of petroleum-soapsuds, 20 to which, if it is desired to dye or illuminate the picture, is added a pigment of the desired color. In this solution the picture is immersed for a period of time, depending upon the thickness of material, the intensity of 25 color desired, and the required shade of the illumination. The picture is then removed from the suds-bath and after being drained is treated, preferably, both front and back, to a thin coat of a compound consisting of equal 30 parts of headlight-oil, lard, hard-oil finish, and strong petroleum-soapsuds, and a small quantity of photographic paste reduced to a milky consistency. The reduction of the paste is preferably, though not necessarily, 35 effected by the addition of a suitable quantity of suds. The picture thus coated is next placed in a second receptacle partially filled with a solution of strong petroleum-soapsuds covered with a thin film of headlight-oil. 40 This second immersion is continued a few minutes, after which the picture is removed, drained and dried, and finally polished with a woolen cloth. The picture thus treated will be found to be beautifully illuminated 45 and highly translucent. Moreover, the color will be intensified and enlivened, and faded tones will be revivified. The image will thus be sharply defined, and it will be found that the translucent coating, while not interfering

with the translucence of the material or the 50 brilliant display of the coloring, will give body or volume to the material and at the same time will protect the picture from the deteriorating action of the air. If desired, the picture thus treated may be backed either 55 by a layer of translucent material or by a backing sufficiently opaque to increase the sharpness of the image.

Obviously the above treatment may be extended to the border of the picture and to the 60 mat if an extended illumination is desired. It will furthermore be evident that all classes of pictures may be subjected to the specified treatment with good results. Wall-paper, newspaper illustrations, and other cheap prints 65 are particularly beautified by the process described.

Petroleum-soap, hard-oil finish, and photograph-paste, herein referred to, are substances purchasable in the market under these names. 70 The petroleum-soap is a soap composed in part of petroleum. The hard-oil finish is a solution of hard gums or resins ordinarily employed as a varnish, and the photograph-paste is a white dextrinous or starchy paste ordinarily employed in the mounting of photographs. It should be distinctly understood, however, that while the particular materials and the exact procedure hereinbefore specified are believed 75 at this time to be conducive to the best results 80 I nevertheless reserve the right to effect such minor variations of the process as may come fairly within the scope of the protection prayed.

What I claim is—

1. That process for the treatment of pictures which consists in first soaking the same in a strong solution of petroleum-soapsuds, next providing the picture with a transparent coating, next immersing the picture in a solution of strong soapsuds covered with headlight-oil, and subsequently drying the picture. 90

2. That process for treating pictures which consists in subjecting the same to the action 95 of petroleum-soapsuds and a pigment, next providing the picture with a transparent coating, next subjecting the coated picture to the

action of petroleum-soapsuds and headlight-oil, and thereafter drying the picture.

3. That process for treating a picture which consists in soaking the picture in a solution of petroleum-soapsuds and a pigment, next coating the picture front and back with a compound consisting of headlight-oil, lard, hard-oil finish, petroleum-soapsuds and photograph-paste, next immersing the picture in a solution of strong suds covered with headlight-

oil, and subsequently drying and polishing the picture.

In testimony that I claim the foregoing as my own I have hereto affixed my signature in the presence of two witnesses.

WILLIAM BUZBY TYLER.
